CLAIM

The ornamental design for an accessory for a virtual reality headset, as shown.

DESCRIPTION

FIG. 1 is a perspective view of an accessory for a virtual reality headset embodying my new design;

FIG. 2 is a perspective view from an opposite side of the accessory for a virtual reality headset embodying my new design;

FIG. 3 is a side view of the accessory for a virtual reality headset embodying my new design;

FIG. 4 is an opposite side view of the accessory for a virtual reality headset embodying my new design;

FIG. 5 is a top view of the accessory for a virtual reality headset embodying my new design;

FIG. 6 is a bottom view of the accessory for a virtual reality headset embodying my new design;

FIG. 7 is a front view of the accessory for a virtual reality headset embodying my new design;

FIG. 8 is a rear view of the accessory for a virtual reality headset embodying my new design;

FIG. 9 is an environmental perspective view of a pair of the accessory for a virtual reality headset embodying my new design positioned on a virtual reality headset; and,

FIG. 10 is an environmental side view of a pair of the accessory for a virtual reality headset embodying my new design positioned on a virtual reality headset.

The broken lines form no part of the claimed ornamental design.
